UNITED STATES PATENT OFFICE.

ROBERT S. GRAHAM, OF PADUCAH, KENTUCKY.

ATTACHMENT FOR TELEPHONE MOUTHPIECES.

Refiled for abandoned application Serial No. 109,364, filed May 15, 1926. This application filed December 27, 1928. Serial No. 328,799.

This invention relates to attachments for telephone mouthpieces or similar apparatus, and aims, among other objects, to provide an improved, simple and inexpensive germicide container which may be readily applied to a mouthpiece for the purpose of destroying disease germs and thereby maintaining the mouthpiece in a sanitary condition to avoid contagion through the inhalation of 5 germs or other impurities by persons using the same. This application is refiled for abandoned application Ser. No. 109,364, filed May 15, 1926.

In the drawing, 15 Figure 1 is a front elevation of the preferred form of the attachment;

Fig. 2 is a vertical, longitudinal section through the device applied to a telephone mouthpiece;

Fig. 3 is a top plan view of the attachment; and

Fig. 4 is a side elevation of the same.

Referring to the drawing, there is shown a main supporting or base member in the 25 form of an annular plate 1, which may be made of celluloid, aluminum or other suitable light-weight material, the front face of which, when applied to a mouthpiece, presents a surface admirably adapted to receive 30 advertising or other matter.

The inner edge of the plate is shown as being pressed outwardly and then bent upon 35 itself to provide a strengthening bead 2, and the margins are then turned inwardly to form a seat 3, into which is adapted to be pressed or clamped the peripheral edges of a wire gauze panel or disc 4 of relatively fine mesh, and made of copper or other non-corrosive wire, which is adapted, when the 40 device is in applied position, to completely cover the mouthpiece, as shown in Figures 1 and 2 of the drawing.

The outer peripheral edge of the annular plate 1 is likewise formed into a continuous 45 bead 5 which, in connection with the inner bead 2, serves to prevent bending or buckling of the annular plate and thereby maintains the wire gauze in tightly stretched condition at all times.

Attached to the inner face of the wire 50 gauze 4, and at the lower portion thereof, is a thin metal container 6 which is round in cross section, and is tapered on a curve towards the rear end to conform to the 55 shape of the telephone mouthpiece, into

which the same projects, the top of the container being horizontally disposed and substantially on a level with the center line of the mouthpiece, and the rear end of said container extending nearly to the rear wall 60 of the mouthpiece, though the said top may be below such level and the said rear end may be somewhat spaced from said wall.

The inner bead 2, at its lower portion, is provided with an arcuate, inclined flange 65 7 extending inwardly therefrom, and the front edges of the container 6 are soldered or otherwise secured thereto, so that the lower portion of the wire gauze abuts against the front wall 6a of the container, as clearly 70 shown in Fig. 2 of the drawing, thus providing communication between the interior of the container and the outside atmosphere.

The upper, horizontal edges of the sides and rear wall of the container 6 are provided 75 with upstanding extensions or lugs 8 within which there is adapted to be seated a cover plate 9, which is preferably formed of non-corrosive metal conforming to the shape of the container and adapted to rest upon the 80 upper edges thereof, said lugs being slightly bent in an outward direction to permit same. The cover plate is provided with a plurality of perforations 9a to permit the passage of 85 fumes or vapors from within the container.

The inner bead, where bent inwardly to form the seat 3, is provided at each side and at the top with inner spring tongues 10 and outer spring tongues 11, suitably spaced apart and said tongues being formed integrally with the annular plate and adapted, when applied in position, to receive and clamp the front circular edge of the mouthpiece.

At the bottom of the inner bead there is 95 only an outer tongue 11 provided, as the aforesaid flange 7 at that point serves to engage the inner edge of said mouthpiece in the same manner as the inner tongues at the sides and top, and to rigidly hold the 100 device in position.

The container is adapted to be packed with raw cotton or other absorbent material, which has previously been saturated with the proper amount of suitable germicide, 105 the vapors from which are adapted to exterminate all germ life that may have been deposited on or within the telephone mouthpiece, and after said cotton has been placed in position and thus treated, the lid 9 is se- 110

cured in position by the lugs 8, when said vapors may freely pass through the apertures 9^a of the cover plate 9 to perform such function, it being understood that the 5 same are neither injurious nor unpleasant to the user of the telephone.

From the foregoing it will be seen that a simple and cheaply manufactured device 10 has been provided which may be readily charged with the absorbent material holding the germicide, that the latter may be held in position against dislodgment and in a packed condition, if desired, by means of the lid or cover 9, and that by simply springing 15 the tongues 10 and 11 and the flange 7 in position over the free, front edge of the mouthpiece 14, the entire device is rigidly held in position thereon, with the rear end of the container adjacent to the rear perforated wall 13 and the rising fumes or vapors having their effect upon the entire 20 interior of the mouthpiece. At the same time, the upper portion of the wire gauze affords ample uninterrupted space for transmitting 25 messages.

Obviously, the present invention is not restricted to the particular embodiment thereof herein shown and described.

What I claim is:—

- 30 1. An attachment for disinfecting telephone mouthpieces comprising an annular plate; a wire gauze panel stretched flat across and marginally supported by the plate; attaching means carried by the ring 35 to hold the gauze panel over the outer edge of the mouthpiece; and a germicide container supported by the plate and projecting into said mouthpiece and occupying substantially the lower half of the same.
- 40 2. An attachment for telephone mouthpieces comprising a flat annular plate having an inner and an outer marginal, reinforcing bead; spring prongs at the inner margin to secure and hold the plate on the 45 outer edge of the mouthpiece; a wire gauze panel marginally held in the inner bead across the mouthpiece; and a germicide container carried by the plate and projecting from the rear side of the gauze into said mouthpiece.
- 50 3. A sanitary attachment for telephone mouthpieces or the like comprising a stiff, flat, annular plate constituting a base member having its inner and outer peripheral

edges formed into stiffening beads; a disc 55 formed of wire gauze having its margins secured to the inner bead; inner and outer prongs carried by the inner bead to frictionally engage the front end of the mouthpiece and support the base thereon with the gauze 60 disc covering the mouthpiece; a rearwardly extending, semicircular flange projecting from the lower portion of the inner bead; a germicide container secured to said flange and extending into the mouthpiece; and a 65 perforated lid or cover for the container.

4. A sanitary attachment for telephone mouthpieces or the like comprising a stiff, flat, annular plate constituting a base member 70 having its inner and outer peripheral edges formed into stiffening beads; a disc formed of wire gauze having its margins secured to the inner bead; inner and outer prongs carried by the inner bead to frictionally engage the front end of the mouthpiece and support the base thereon with the gauze 75 disc in covering relation to the mouthpiece; a rearwardly extending, semi-circular flange projecting from the lower portion of the inner bead; a semi-circular container 80 having a front wall and supported by said flange; said container extending into the mouthpiece and occupying the lower portion of the space therein; the rear end of the container being closed, the upper edges of the 85 sides and rear wall of the container being horizontal and provided with upstanding lugs; and a perforated lid or cover conforming to the container and adapted to be held thereon by said lugs, after the same 90 has been packed with medicated cotton or the like.

5. A disinfecting attachment for telephone mouthpieces comprising, in combination, a plate having a speaking opening; 95 clips at the edge of the opening adapted to be clamped on the end of the mouthpiece; a screen secured across the speaking opening; and a germicide receptacle secured to the rear side of the plate and so shaped 100 that it projects into the lower half of the mouthpiece leaving a space for fumes to circulate between it and the inside wall of the mouthpiece.

In testimony, that I claim the foregoing 105 as my own, I have hereto affixed my signature.

ROBERT S. GRAHAM.
